UNITED STATES PATENT OFFICE.

FRANCIS W. BRADY, OF ENGLEWOOD, NEW JERSEY, ASSIGNOR TO ELECTRIC BOAT COMPANY, OF NEW YORK, N. Y., A CORPORATION OF NEW JERSEY.

AUTOMATIC DIVING MECHANISM FOR SUBMARINE BOATS

SPECIFICATION forming part of Letters Patent No. 738,879, dated September 15, 1903.

Application filed February 25, 1902. Serial No. 95,628. (No model.)

To all whom it may concern:

Be it known that I, FRANCIS W. BRADY, a citizen of the United States, residing in Englewood, Bergen county, New Jersey, have invented certain Improvements in Automatic Diving Mechanisms for Submarine Boats and the Like, of which the following is a specification.

In order that the present invention may be the better understood, it will be proper to state here that in the class of submarine boats, including also the class of automatically-operated boats known as "torpedoes," an engine is employed to actuate the diving-rudders, and the valve of this diving-engine is automatically operated and controlled, in order to cause the boat to dive to a predetermined depth, by a flexible diaphragm exposed on one side to pressure from the water in which the boat is submerged and on the other side to the pressure of a spring the tension of which is capable of regulation or adjustment. The diaphragm actuates a floating-lever, which latter modifies the action of the valve of the diving-engine, thus controlling the diving-rudders. The water-pressure and the spring, acting automatically on opposite sides of the diaphragm, therefore control the movement of the boat in a vertical direction. When the boat is at the surface on a level keel and the diaphragm-spring is set for a predetermined depth of dive, this spring sets the diving-rudders over fully into their diving position, so that as soon as the boat is set in motion ahead it begins to dive, descending obliquely. As it continues to descend the hydrostatic pressure on the diaphragm opposing the spring increases with the depth until at a predetermined depth the two forces will exactly balance each other. The valve of the diving-engine will then be at the center of its travel, and the diving-rudders will be at "steady" or be aligned with the axis of the boat. The path followed by the boat in its descent will be a curve of gradually-increasing radius, because the inclination of the diving-rudders is greatest when the boat is at the surface, and this inclination gradually decreases as the boat descends; but when the boat shall have reached the pre-

determined depth and the diving-rudders are thereby brought into alignment with the axis of the boat the boat's axis will not be horizontal, as it should be. In fact, said axis will cross the plane of predetermined depth at a very considerable angle, and the reverse curve necessary to bring the boat to a level keel must be described below the level or plane of predetermined depth until the boat rises again and traverses said plane from below at a considerable angle. The objection to this controlling means is that if the depth of water should not much exceed the desired depth of submergence at the point where the boat dives it is obvious that the latter will strike the bottom, and this will be almost certain to seriously disable the boat, particularly if the bottom be rocky.

In view of the above conditions the purpose of the present invention is to provide automatic means operating in conjunction with the means above described for confining the formation of the reverse curve in the boat's path downward to a depth not exceeding that of the predetermined submergence, whereby the diving-boat will be brought to the plane of submergence with a level keel. This is effected by providing automatic means operating in conjunction with but in a measure independently of the means above described for giving to the diving-rudders a reversing inclination when the boat shall have descended to a depth which is such a fraction of the total depth of submergence as may be found by experiment suitable for a particular boat. The effect of thus reversing the inclination of the rudders is to cause the boat at the moment of reversal to change its direction and follow a curved path, which is the reverse of that it was before following, the new curved path being tangent to the plane of predetermined depth of submergence, thus bringing the boat to a level keel at the proper depth and eliminating the danger due to the boat's descending materially below said depth.

In the accompanying drawings, which serve to illustrate an embodiment of the invention, Figure 1 is a diagrammatic view illustrating the path of the boat in diving. Figs. 2 and

3 are respectively an under side view or plan and a side elevation of the rear portion of a boat provided with the improved diving mechanism. Parts of the boat-body are broken 5 away to show the mechanism. Fig. 4 is a sectional elevation of the diving engine and mechanism on a larger scale, and Fig. 5 is a plan view of the parts at the sliding fulcrum of the floating lever. The elements of the 10 mechanism in Fig. 4 are arranged somewhat differently from the principal views merely to illustrate all of the parts better.

Referring primarily to Fig. 1, *x* represents the water-line. *y* is the predetermined plane 15 of submergence, and *z* is the bottom of the waterway. The boat *a* is represented in full lines as at the water-level, ready for diving. By the ordinary means employed for controlling the diving-rudders the boat would follow 20 the curved path, indicated by dotted lines at *x'*, eventually crossing the plane *y*, as indicated at *a'*. With the improved means, which form the embodiment of this invention, the boat will change direction at some point, 25 *y'*, and follow the reversed curved path indicated by the dotted lines *x''* and reach the plane *y* on a level keel, as at *a''*. This diagrammatic view will suffice to illustrate the purpose of the invention, which will now be 30 more particularly described with reference to the detail views.

In the views, *a* represents the boat or boat-body; *b*, the diving-rudders usually secured on a common shaft *c*. *d* is an arm on said 35 shaft from which an operating-rod *e* extends into the boat and there becomes the piston-rod of the diving-engine *f*, as seen in Fig. 4. It need only be said of this engine that *g* is the piston secured to the rod *e*.

40 *h* is the valve-chest.

i is the inlet for the fluid under pressure which moves the piston, and *j* is a double-piston valve which normally controls the ports of the engine. In the ordinary or known constructions of mechanisms for controlling the 45 diving-rudders of a submarine boat heretofore briefly described the valve *j* or one similar thereto is employed alone to control the ports of the engine.

50 *k* is the stem of the valve *j*.

m is a rocker having a non-rotative journal or pivotal axis *n*. A floating lever *o* has a pivotal journal or fulcrum *p*, adapted to slide horizontally a limited distance at the 55 same level as the axis *n*. On the journal *p* is loosely mounted a rocking cross-arm *q*, to which the valve-stem *k* is coupled above the center of *p*. The arm *q* carries at its respective extremities two studs *r r*, which engage 60 open slots *m'* in the transverse branches of the rocker *m*. This is to permit the fulcrum *p* to play in its guides and permit the cross-arm *q* to maintain its connection with the rocker *m*. The longer arm of the rocker *m* (see Fig. 4) is coupled to a block which slides 65 in a slotted guide-piece *t*, secured to the piston-rod *e*. The shorter arm of the lever *o* is

coupled to a rod *u*, which extends to the conning-tower or other locality and has on it rack-teeth, gearing with a pinion *u'*, Fig. 70 4, under control of the steersman or other person operating the boat. The longer arm of the lever *o* is coupled by a link *v* through a regulating device to a diaphragm-rod *w*. This rod is coupled to a diaphragm *2* in a diaphragm-casing *1*, which is open to the water-pressure outside of the boat through a pipe *3*. The rod *w* is coupled at its other end to a lever *4*, and a spring *5*, attached to this lever, acts antagonistically to the water-pressure. 80

It may be explained here, although this feature is not claimed specifically in this application, that the studs *r r* are disposed as seen in Fig. 4 when the piston *g* is at mid-stroke—that is, each stud will be entered about half 85 its diameter into the respective slots in the rocker *m*. Now if the fulcrum *p* be shifted the rocking cross-arm *q* will move with it, thus moving one of the studs *r* out of engagement and the other into engagement with 90 the rocker *m*. By shifting the fulcrum *p* in the other direction while the rudder is at “steady” the other stud *r* will engage the slot in the other arm of the rocker *m*. Thus one stud *r* is moved into engagement when the 95 other moves out. The farther the stud is moved in toward the fulcrum *n* of the rocker *m* the shorter will be the leverage with which the slotted arm acts on the stud *r*, and the purpose of this is to limit and control the extent of movement of the piston.

The above features are only illustrated herein as used conjointly and in operative combination with the novel features now to be described.

105 6 is a diaphragm-casing containing a diaphragm *7* and open to the water-pressure at 8. This diaphragm *7* has a rod *9*, which is coupled to a lever *10*, and a spring *11*, connected to this lever, antagonizes the water-pressure on the diaphragm *7*. The rod *9* is coupled by a link *12* to one arm of an elbow-lever *13*, fulcrumed at *14*, and the other arm of said lever *13* is coupled to the stem *15* of a cylindrical hollow valve *16* in the chest *h* 115 of the diving-engine. This valve incloses the double-piston valve *j*, before described, and serves to modify the action of the latter. The tension of the respective springs *5* and *11* may be regulated by the screw connections seen 120 in Fig. 2, which form regulating devices *17* and *18*. The diaphragm *2* and the valve *j* may be called, for distinction, the “diving-diaphragm and valve” and the diaphragm *7* and the valve *16* the “reversing-diaphragm and 125 valve.” The function of the former is to bring the rudders from the extreme diving inclination to steady, and the function of the latter is to shift the rudders quickly to an upward inclination and then leave them under control of the diaphragm *2*. The tension of the spring *11* is so adjusted and set as to yield only when the boat shall have descended to 130 the predetermined depth at which the rud-

ders are to be reversed or shifted to an upward inclination.

It will be understood that when the boat is at the surface, as at *a* in Fig. 1, the parts 5 will be in the position seen in Fig. 4—that is, the diving-rudders will be at steady or parallel with the boat's axis, and the piston *g* and the valves *j* and 16 will be in the positions shown.

10 The operation is as follows: When the boat is to dive, the operator or steersman through the medium of the pinion *u'* and rod *u* operates the lever *o* and valve *j*, so as to admit the fluid or liquid (usually oil) to the cylinder of the diving-engine *f*, Fig. 4, to the right of the piston *g*, thus driving it to the left-hand end of the cylinder and causing it to turn the diving-rudders *b* to the extreme diving inclination downward. The boat is then 15 started ahead and it dives, descending in a curved path. The valve *j* having shifted back again, the point *o'*, where the rod *u* is coupled, becomes a fulcrum of the lever *o*, and as the boat descends the hydrostatic 20 pressure acts on the diaphragm 2 to overcome the spring 5 and through the floating lever *o* and cross-arm *q* to shift the valve *j* and admit fluid to the left-hand end of the cylinder for moving the piston to the right, thus bringing 25 the rudders *b* toward steady; but the movement of the piston and its rod acts on the valve-stem through the guide-piece *t*, rocker *m*, and cross-arm *q* tend to counteract this movement of the valve *j*, and the combined 30 action of the two mechanisms results in the gradual shifting of the diving-rudders toward steady by relatively slow increments. When, however, the boat shall have reached a depth predetermined where the downward curve of 35 its path is to be reversed—as at *y'* in Fig. 1, for example—the hydrostatic pressure will act on the diaphragm 7 of the curve-reversing mechanism, and the operation of this mechanism will be described. Let it be supposed 40 that the piston *g* has traveled from the left-hand end of the cylinder in Fig. 4 about one-fourth of its entire travel and the valve *j* is just closing the ports in the tubular valve 16, which latter ports are always open 45 to those of the cylinder. As the diaphragm 7 is pressed inward, carrying with it the rod 9, it swings the toggle-link 12 quickly to a position at right angles to the rod 9, thus acting to rock the elbow-lever 13 quickly. This lever 50 acts through the rod 15 to shift the valve 16 its full stroke to the left in Fig. 4 and open the left-hand end of the cylinder to the liquid under pressure. The effect of this will be to drive the piston *g* rapidly to the right-hand end of the cylinder and through the rod 55 *e* to turn the diving-rudders *b* to their upward inclination. The curve of the boat's path will now be reversed; but as the boat continues to descend the diaphragm 7 will continue to 60 move in; but its action on the link 12 will now be such as to draw in the shorter arm of the lever 13, and thus cause said lever to at

once return the valve 16 to its first or normal position, leaving the diving-rudders again under the control of the diaphragm 2; but 75 the movement of the piston to the right, as stated, will have shifted the valve *j* so as to admit the liquid under pressure to the right-hand end of the cylinder, and the effect will be to gradually bring the diving-rudders to 75 steady from their upwardly-inclined position, and they should reach the position of steady 80 when the boat shall have reached the predetermined depth of submergence with an even or level keel, as at *a''* in Fig. 1. Thus it will be seen that the diaphragm 7 serves to rather suddenly actuate the diving-engine at a predetermined depth, so as to reverse the inclination of the diving-rudders, and then to shift the valve 16 back to its first position, leaving 85 the rudders under the control of the diaphragm 2 and the piston.

To prevent the spring 11 from actuating the valve 16 when the boat rises toward the surface and the pressure on the diaphragm 7 is 90 removed, means may be provided for locking or holding the rod 9 against return, and this may be a spring-pawl 17' on the guide 18', adapted to engage a shoulder 19 on the rod. This device is seen in Fig. 4.

95 The invention has been described as employed in connection with a diving mechanism not herein claimed, to which the new mechanism has been fitted, so as to act in conjunction therewith; but I do not wish to 100 limit myself to the specific features of construction as herein shown, as I am well aware that these may be varied without departing from the spirit of my invention. For example, it is not material just how the spring 5 105 shall be disposed so long as it serves its purpose. The valves *j* and 16 have been arranged one within the other; but so long as they are so disposed as to perform their proper functions the specific arrangement is not very important. I should consider any diaphragm 110 device adapted to automatically shift the diving-rudders at a predetermined depth so as to reverse the curvature of the boat's downward path and to again act automatically to 115 leave them under control of the normal diving-diaphragm as coming within the scope of my invention. Moreover, the diaphragm devices herein shown being old in themselves any 120 equivalent device, as a piston in a cylinder, which is also well known, might be substituted therefor.

125 The diaphragm device shown is selected merely because it has been found most satisfactory in practice.

It may be explained that in this class of devices the regulating device referred to is merely to regulate the coupling connection of the floating lever *o* with the diaphragm-rod *w*, and it comprises a dog *v'*, carried by 130 a lever *v*, fulcrumed on a sleeve *v*, fixed on the rod *w* and carrying a toothed rack *v* for the dog to engage. The link *v* is coupled to the shorter arm of the lever *v*.

Having thus described my invention, I claim—

1. In a submarine boat, the combination with the diving rudder or rudders, the diving-engine and its valve, the floating lever, the rocker and the diaphragm device controlling the rudder normally in diving, of means for throwing up the diving-rudders above the axis of the boat at a predetermined point of submersion, to reverse the curvature of the descending path, said means comprising a reversing-valve for the diving-engine, for modifying the action of the diving-valve an auxiliary diaphragm mechanism, and a toggle mechanism comprising the lever 13 and link 12 between said diaphragm and reversing-valve, whereby the former controls the latter.
2. In a submarine boat, the combination with the diving rudder or rudders, the diving-engine and its valve, the floating lever, and the diaphragm device controlling the rudder normally in diving, of means for throwing up the diving-rudders above the axis of the boat at a predetermined point of submersion, to reverse the curvature of the descending path, said means comprising a reversing-valve 16, its stem 15, the elbow-lever 13, to one arm of which said valve is linked, the rod 9, the link 12 coupling said rod to the other arm of the lever 13, the diaphragm 7, connected to the rod 9, the diaphragm-casing, open to the water of flotation, and a spring which antagonizes the pressure of the water of flotation on said diaphragm 7.
3. In a submarine boat, the combination with the diving rudder or rudders, the diving-engine and its valve, the floating lever, and the diaphragm device controlling the rudder normally in diving, of means for throwing up

the diving-rudders above the axis of the boat at a predetermined point of submersion, to reverse the curvature of the descending path, said means comprising a reversing tubular valve 16, inclosing the main or normal valve of the diving-engine, an auxiliary diaphragm device under control of the pressure of the water of flotation, and mechanism comprising a lever and toggle-link between said diaphragm device and reversing-valve whereby the movement of the diaphragm in one direction under the influence of the water-pressure, imparts a reciprocating movement to said valve 16.

4. In a submarine boat, the combination with the diving-rudders, the diving-engine and its valve, and the diaphragm device and mechanism for controlling the rudders normally in diving, of means for throwing up the diving-rudders above the axis of the boat at a predetermined point of submersion, to reverse the curvature of the descending path, said means comprising a diaphragm device, the reversing-valve and its stem, the elbow-lever having one of its arms coupled to the rod of the reversing-valve, the link 12, coupled at one end to the other arm of the elbow-lever, and the other end to the stem of the diaphragm device, a lever and spring which antagonizes the pressure on the said diaphragm device, and means for locking the diaphragm-rod when the diaphragm is shifted.

In witness whereof I have hereunto signed my name, this 20th day of February, 1902, in the presence of two subscribing witnesses.

FRANCIS W. BRADY.
